Niagara Falls, N. Y., a corporation of New
York

Original application January 26, 1937, Serial
No. 150,579. Divided and this application
April 10, 1939, Serial No. 267,205

2 Claims. (Cl. 226—14)

This invention relates to a method of packing foodstuffs and more particularly to a method of packing elongated tapered food articles, such as corn on the cob or carrots, into cans. This application is a division of my co-pending application for Patent Serial No. 150,579, filed January 26, 1937 for Apparatus for packing foodstuffs.

The principal object of the invention is to provide a process for packing tapered articles, such as corn on the cob or carrots, which insures the maximum fill in each can of the most desirable portion of each article, the articles being placed in an open ended mold and the operator placing approximately half of the tapered articles with the tapers running in one direction and the other half with the tapers running in the opposite direction and then adjusting the articles so that the maximum fill is obtained in the mold, the ends of the articles projecting from the mold being subsequently severed by trimming knives and the contents of the mold being then transferred into a can.

Another object is to provide such a process which can be carried out quickly and expeditiously and with apparatus in which the molds can be quickly filled and the articles adjusted to secure the maximum fill, the remaining operations being effected automatically.

Another object is to provide such a process in which the operation of filling the molds and adjusting the tapered articles in the molds can be effected while the molds are traveling along a feeding station, the process being thereby adapted to a continuous can filling operation.

In the accompanying drawing:

Fig. 1 is a fragmentary vertical longitudinal section through an apparatus for packing foodstuffs suitable for use in carrying out my process.

Fig. 2 is a fragmentary horizontal section, taken on line 2—2, Fig. 1.

Fig. 3 is a view similar to Fig. 2 and showing, diagrammatically, the manner in which the contents of the molds are transferred into cans after the ends of the articles have been cut to the proper length.

The figures illustrate that portion of a packing apparatus necessary to show the steps of the present invention, a complete disclosure of this apparatus being contained in my said co-pending application Ser. No. 150,579, of which the present application is a division, reference being made thereto for a detailed disclosure of this apparatus. The apparatus is shown as comprising a bed 5 which is traversed by an endless chain 6,

this chain carrying a plurality of spaced two-part, open ended molds 7.

Each of the two-part molds 7 comprises a semi-cylindrical part 8 which is secured to the chain 6 by a pair of ears 9, which ears form part of the chain linkage, and a relatively movable semi-cylindrical section 10 which is pivotally secured at one edge to the corresponding edge of the section 8 by a pivot pin 11, the sections 8 and 10 being thereby hinged and capable of being opened and closed in the manner of a clam shell. The opening movement of the section 10 relative to the section 8 is limited by the engagement of a lug 12 projecting outwardly from the back of the section 8 adjacent the hinge 11 with a similar lug 13 projecting outwardly from the back of the section 10. The section 10 is normally held in its open position by a C-shaped spring 14, the back of which passes around the hinged connection between the two sections and the ends of which can be secured to the sections 8 and 10 in any suitable manner.

The section 10 of each of the molds is also formed to provide two pairs of outwardly projecting ears 15, the forward pair of ears carrying a roller 16 and the rearmost pair of ears carrying a roller 17. These rollers 16 and 17 cooperate with a stationary track to close the molds in a certain order, as hereinafter described, these rollers being released following the transfer of the molded contents from each mold into the cans to be filled, the springs thereupon opening the mold sections so as to permit the ready insertion, by hand, of the articles to be packed. While traversing the bed 5 the molds are held in an expanded condition by the springs 14, this readily permitting the insertion of the corn cobs or carrots into the open ends of the molds.

The packing of corn on the cob is illustrated, and in so packing corn on the cob an operator on one side of the bed 5 first places half the number of ears to be packed in the bottom of each mold 7. In the illustration it is assumed that the cans receive four ears and therefore the first operator places two ears 18 in each mold cavity. 45 These ears are inserted tip first from one end of each mold as illustrated at the right of Fig. 2. The half filled mold then moves on to the next operator at the opposite side of the machine, who inserts the other two ears 19, tip first, from the opposite side of the mold. This operator then adjusts the ears so that the mold cavity is filled to the maximum extent. This can be done because the upper two ears 19 taper in the opposite direction from the lower two ears 18 and hence 55

the ears can be adjusted axially either as a group or individually to secure the maximum amount of kernels in the mold cavity.

After the molds pass the filling station the roller

- 5 16 of each mold strikes the opposing face 29 of a U-shaped bracket 21 which is mounted to straddle the chain 6 and the procession of molds carried thereby. This engagement causes each movable mold section 10 to be swung rearwardly toward 10 the corresponding mold section 8 and as the forward movement of the chain continues the roller 16 rides onto a cam face 22 provided on the underside of the bracket 21. This cam face 22 effects the final closing movement of each mold passing 15 under the bracket 21 and when completely closed the rollers 16 and 17 ride onto a track 25 which holds the passing molds firmly closed and the contents compressed.

While so held in a closed condition by the track

- 20 25, the molds pass two pairs of rotary knives 26 and 27. These knives are suitably guarded by a casing 28 and are both mounted on a shaft 29 so as to be rotated at high speeds. As the molds pass between the knives 26, 27, the ends of the 25 cobs projecting from the open ends of the molds are cut off, these cuttings falling into a pair of chutes 30, 31 from which they can be discharged into any sort of a receptacle placed under the open lower ends of the chute. It will be seen that the articles contained by the molds are all 30 cut to a length determined by the spacing of the knives 26 and 27, this being, of course, determined by the size of the cans which are being filled.

- 35 35. After passing the knives 26, 27 the molds pass into alignment with one or more plungers 34, these plungers being preferably mounted to move in unison with the molds in a manner disclosed in detail in my said co-pending application Serial 40 No. 150,579. These plungers move axially into the molds so as to transfer the trimmed tapered

articles into cans 35 which are brought into position on the side of each mold opposite the plungers 34 in any suitable manner.

It will be seen that by placing the ears of corn in the molds in such manner that half of the 5 ears taper in one direction and the other half taper in the opposite direction, the maximum fill can be obtained and also the ears maneuvered so that the most desirable kerneled portion of each ear is packed in the can.

10 I claim as my invention:

1. The method of packing elongated tapered articles in cans which consists in arranging a part of said articles with their tapers running in one direction, arranging the balance of said articles alongside said first part with their tapers running in the opposite direction and molding all of said articles to a bunch of predetermined cross sectional form, adjusting the articles lengthwise relative to one another to obtain the maximum 20 fill within a predetermined molding space, cutting off the ends of the articles projecting beyond said molding space and transferring the cut articles from said molding space to a can of similar proportions.

2. The method of packing elongated tapered articles in cans which consists in inserting approximately half of the articles lengthwise into an open ended elongated mold and with their tapers running in one direction, inserting the balance of the articles tip first into said mold with their tapers running in the opposite direction, adjusting said articles lengthwise relative to one another to obtain the maximum fill within said mold, contracting the walls of said mold to firmly hold the adjusted articles therein, cutting off the ends of said articles projecting out from said mold and transferring the cut articles from said mold into a can of similar proportions.

40 WILLIAM DE BACK.
